US00D560110S

(12) **United States Design Patent** (10) **Patent No.:** **US D560,110 S**
(45) **Date of Patent:** **** Jan. 22, 2008**

(54) **KNOB**
(75) Inventor: **Michael Hart Ricereto**, Baltimore, MD
(US)
(73) Assignee: **Newell Operating Company**, Atlanta,
GA (US)
(**) Term: **14 Years**
(21) Appl. No.: **29/276,263**
(22) Filed: **Jan. 19, 2007**
(51) LOC (8) Cl. **08-06**
(52) U.S. Cl. **D8/310**
(58) Field of Classification Search D8/300,

(57) **CLAIM**

I claim the ornamental design for a knob, as shown and described.

DESCRIPTION

FIG. 1 is an elevated perspective view of the knob of the present invention;

FIG. 2 is a front view of the knob shown in FIG. 1;

FIG. 3 is a side view of the knob shown in FIG. 1, each side view being identical thereto; and,

FIG. 4 is a rear view of the knob shown in FIG. 1.

Features shown in broken lines in the drawings are not part of the claim.
